STANLEY D. LIVINGSTON, OF NEW YORK, N. Y., ASSIGNOR TO EISEMANN MAGNETO CORPORATION, OF BROOKLYN, NEW YORK, A CORPORATION OF NEW YORK.

RADIO TUNING INSTRUMENT.

Application filed December 21, 1922. Serial No. 608,216.

My invention relates to instruments used in tuning radio circuits, and its object, broadly stated, is to provide improved devices embodying distinctive features of 5 novelty with consequent advantages in construction and operation.

In radio receiving sets as heretofore constructed, the knobs for adjusting the various units within the box or cabinet are mounted 10 on the front panel in such a way that they protrude therefrom for their entire length or thickness. Where double knobs are used, as in vernier condensers or vernier rheostats, the smaller knob projects beyond the 15 larger. These protruding knobs not only detract from the appearance and neatness of the receiving set as a whole, but they are frequently in the way. Thus, a previously 20 adjusted knob is liable to be struck accidentally by the operator and moved out of adjusted position.

One of the features of my invention eliminates the foregoing objections and disadvantages of protruding knobs by means of a recessed or cup-shaped plate adapted to house 25 the knob or other hand member of the instrument. When this plate is secured over an opening in the front panel, the rotary hand member is practically flush with the panel. 30 This flush mounting is applicable in all radio units requiring adjustment by means of a rotary member—such as variometers, variocouplers, variable condensers and rheostats, potentiometers, and so forth.

35 In place of the usual round knob heretofore employed for adjusting those instruments, I prefer to use a bar which is more conveniently and steadily gripped by the fingers, thereby permitting a delicate adjustment to be made more easily and quickly. A mark at one end of the bar acts as a pointer, which moves close to a scale on the rim of the disk. For instruments requiring a double adjustment—such as, vernier 40 condensers, vernier rheostats, and the like—I provide the bar with a central recess adapted to receive a small knob, which is thus practically flush with the front of the bar. When the bar and knob are gripped as a 45 single member, they rotate together, but the knob is readily adjustable independently of the bar.

Another feature of my invention generally

applicable to various radio units, is the mounting of the instrument on the cup-shaped plate previously referred to. This plate is preferably made of metal and carries a bracket at the back for attaching thereto the outer fixed frame of the instrument and all parts carried thereby. I prefer to provide the bracket with a shaft bearing for the rotatable element of the instrument. This provides a very simple and yet secure support for the entire instrument and makes it an easy matter to mount the 55 same on a panel of the receiving set. The metal plate offers the additional advantage that, when grounded, it acts as a capacity shield. The panel may, therefore, be of 60 metal. 70

Certain features of my invention are particularly applicable to variable inductance units like variometers and variocouplers, where a substantially spherical or partly spherical member rotates within the chamber of a fixed member. The rotary member is usually called the rotor, and the stationary member is termed the stator. As known to those who are familiar with such prior devices, the rotor comprises a hollow spherical segment or shell of insulating material on which is wound a coil of wire. Heretofore, it has been the practice to mold this shell in two halves separated in a plane at right angles to the axis of the segment; or, 80 to put it differently, in a plane substantially parallel to the planes of the coil windings. This method of making the shell halves is objectionable for several reasons. For instance, it requires separate means for 85 holding the shell parts together, and also requires the separate insertion of metal bushings in the line of axial support. Then again, the shell halves as previously constructed, although spherical on the outside, 90 are cylindrical on the inside, thus possessing walls of considerable thickness, especially at the middle. Thick walls of dielectric material are objectionable in devices of this kind, as every radio engineer understands. 95 100

My new construction of rotor obviates the foregoing objections of prior devices. In molding the shell halves, I make the line of separation in a plane parallel to or passing through the axis of the spherical segment; which is the same as saying, in a 105

plane substantially at right angles to the planes of the coil windings. In the preferred method of molding, the axial point of support for each shell half is at the bottom of the mold, so that the metal bushing required at that point can be placed in the mold before the plastic material is poured in. When the molded half is then taken out, the metal bushing is in its proper place. 10 Also, in my construction, the winding itself holds the two halves rigidly together, without the need of separate fastening means. Furthermore, the walls of the shell as thus constructed are uniformly thin and 15 yet of sufficient rigidity.

Referring specifically to the so-called variocouplers, my invention provides certain advantages over prior instruments of that type. As heretofore constructed, variocouplers have the primary winding on the stator and the secondary winding on the rotor. The primary winding is tapped at different points, which connect to a separate tap switch mounted on the panel. This switch 20 is controlled by a knob which moves a connecting arm over a series of contacts. In my new construction of variocoupler, I do away with this outside tap switch by mounting the tap switch on the rotor itself as a 25 part of the instrument. The rotor winding is preferably the primary, but it may be the secondary. In the preferred form, the switch in my variocoupler is controlled by a knob nested in the bar which operates the 30 rotor and which is housed in the cup-shaped supporting disk previously mentioned. In this way, the variocoupler and tap switch become a single unit and are mounted on the panel as a single piece of apparatus.

40 The foregoing and other features and advantages of my invention will be clearly understood from a detailed description of the accompanying drawings, in which

45 Figure 1 is a front elevational view of a variocoupler constructed in accordance with my invention;

Fig. 2 is a side elevation of the instrument shown in Fig. 1;

50 Fig. 3 is a detached view, partly in section, of the supporting plate with its attached bracket on which the frame of the variocoupler is mounted;

Fig. 4 is a rear perspective view of the supporting bracket;

55 Fig. 5 is a longitudinal cross-section approximately on line 5-5 of Fig. 2, looking downwardly;

60 Fig. 6 is a transverse cross-section approximately on line 6-6 of Fig. 2, showing the tap switch mounted on the rotor;

Fig. 7 is a top plan view of the variocoupler shown in the preceding figures;

65 Fig. 8 is a rear view of the finger bar by means of which the position of the rotor is controlled;

Fig. 9 is an inside view of one of the shell halves which constitute the frame or body of the rotor;

Fig. 10 is an inside view of the other half of the rotor shell;

Fig. 11 is a front elevational view of a variometer embodying certain features of my invention; and

Fig. 12 is a longitudinal cross-section approximately on line 12-12 of Fig. 11, looking downwardly.

The variocoupler illustrated in the drawings comprises a stationary member or stator indicated as a whole by S, and a rotary member or rotor designated as a whole by R. I might say here that the drawings show the instrument substantially in full size. The frame or body of the stator, in the particular instance illustrated, consists of a pair of complementary shells 1 and 2 which, when fitted together, meet along a line or plane 3 and form a hollow frame or support. The inside of this frame forms a substantially spherical chamber C, within which the rotor is operatively mounted. The shell members 1 and 2 are made of a suitable insulating material, of which there are several kinds on the market for that purpose. In practice I have made the stator frame of a composition commonly called bakelite, which may be molded thin and yet possesses sufficient rigidity. The stator shell 1 is formed with a rib or flange 4 at the front, and has a rib or flange 5 at the rear end. Similarly, shell 2 has a front flange 6 and a rear flange 7. When the two shells are assembled, the rear flanges 5 and 7 fit together, as shown in Fig. 7, and receive bolts 8 or other fastening means. The front ribs or flanges 4 and 6 of the stator are spaced apart to receive a flange or flanges 9 projecting rearwardly from a plate 10. The projecting member or members 9 may be regarded as an arm or rib extending from the base plate 10 in a direction at right angles to the plane of the plate. The parts 9 and 10, which are best shown in Figs. 3 and 4, may be cast in a single piece; preferably of metal. For convenience I shall call this member a bracket, which I have marked K. The flanges 9 of bracket K have holes 11 arranged in alignment with holes 12 in flanges 4 and 6 (see Fig. 7), and through these aligned openings pass suitable fastening means such as bolts 13. It will be seen that the shell or frame of the stator S is rigidly mounted on bracket K.

This bracket is provided with a central hub or bushing 14 (see Figs. 3 and 4) arranged to project into an opening 15 in the stator S, as shown in Fig. 5. As will presently be explained, the hub 14 forms the front bearing for the rotor shaft. In the broader aspect of my invention, the particular construction or configuration of the stator shell

is immaterial, provided only that it properly cooperates with the rotor. When I speak of the stator chamber C as substantially spherical, I use the expression in a loose sense to describe a chamber adapted to accommodate the rotor.

On the inside of the stator is mounted a winding 16, which will be referred to as the stator winding. The turns of wire which 10 constitute this winding are laid against the inside wall of the stator frame or shell, as may be seen in Figs. 5 and 6. In the present instance, the winding 16 is the secondary, but in the broader aspect of my invention this winding might be made the primary. The two ends 17 and 18 of the stator winding 16 are electrically connected to a pair of binding posts 19 and 20, respectively, mounted on the stator, as best 20 shown in Fig. 5. The ends 17 and 18 are led through openings 21 in the stator shell and are permanently secured to the binding posts 19 and 20. Thus, by simply clamping the ends of the proper conductors to 25 binding posts 19 and 20, which are easily accessible, the winding is connected in the radio circuit. As seen from Figs. 5 and 6, the stator winding 16 is in two halves or sections, one half being on shell 1 and the other half on shell 2. These two coil 30 sections are electrically connected together by a wire 22, which passes through openings 23 at the rear end of the stator shell (see Fig. 2). In this way, the two halves of the 35 stator winding form in effect a single coil.

I will now describe the rotor R, which is mounted within the chamber C of the stator. The body of the rotor, as herein illustrated, 40 consists of a pair of shells 24 and 25, which are substantially semi-spherical in shape and, when fitted together, form a hollow spherical segment or what some might call a truncated sphere. Of course, I use these terms, not in their strict mathematical sense, but 45 rather in a practical way to denote the general shape of the rotor. The general contour of the complete rotor shell is such that it fits rather closely within the chamber C, of the stator, as may be seen from Figs. 5 and 6. Attention is called to the fact that the shell halves 24 and 25 are separated along 50 a line or plane 26 (see Figs. 2 and 5), which may be described as passing through or parallel to the axis of the spherical segment. For the sake of clearness, I might 55 explain that the axis of the rotor shell or segment is an imaginary line passing through the centers 27 of the circular openings 28 formed at diametrically opposite 60 ends of the rotor shell. To assist in fitting the shell halves 24 and 25 together, I provide the edges of member 24 with a lug 29 and a recess 30, while the corresponding edges of the other shell member are provided 65 with a recess 31 and a lug 32. When

the two shell halves are fitted together, lug 29 snaps into recess 31 and lug 32 enters recess 30. After the rotor is thus fitted together, it is ready to receive a winding 33, which consists of turns of wiring coiled on or around the outer surface of the shell. It will be observed that these coil windings are laid in planes substantially at right angles to the plane of separation of the shell halves 24 and 25, whereby these windings 70 also serve as a means for securing the shell halves together. This is a decided advantage because it dispenses with separate fastening means which are necessary in rotors heretofore constructed. In these prior devices, the two sections of the rotor are separated along a plane roughly indicated by the dotted line x-x in Fig. 5. As will be seen, the plane x-x is substantially parallel 75 to the planes of the coil windings of the rotor, so that additional fastening means are required in these prior rotors to hold the shell halves together. I dispense with these separate fastening means altogether by constructing the rotor shell as above described. 80 It is clear that the plane of separation of the shell members 24 and 25 need not be in the direction indicated at 26, but may be in any direction substantially parallel to the axis 85 27 or any plane cutting through the planes 90 of the rotor coil winding.

There is another advantage in my new rotor shell. The shell members 24 and 25 are molded out of a suitable insulating composition, such as bakelite. Referring to Figs. 5, 9 and 10, it will be seen that shell member 24 has embedded therein a screw-threaded metal bushing 34, while the other shell member 25 has embedded therein a metal bushing 35. When the shell halves 100 are assembled, the metal bushings 34 and 35 are in axial alignment, as best shown in Fig. 5. In the process of molding the shell halves 24 and 25, the bushings 34 and 35 105 are preferably placed at the bottom of the steel molds, which are then charged with the fluid or plastic molding material. When the shell half is taken out of its mold, the axial bushing 34 or 35 is firmly embedded in the molded material. This embedding of the metal bushing in a single 110 operation is not possible in rotors where the shell halves are separated in a plane passing through the axial supports of the rotor, as indicated by the dotted line x-x 115 in Fig. 5. In that case it was necessary to insert the metal bushings separately after the shell halves had been molded. Furthermore, in molding the rotor shell halves according to my invention, it is possible to 120 make the walls of uniform thickness, or perhaps I should say thinness. As all electrical engineers understand, it is desirable in these radio instruments to have the dielectric material as thin as possible, and I 125 130

secure this advantage in my rotor construction.

Although I have shown the rotor in substantially spherical form, it is clear that it 5 may be designed in any other practical shape adapted to rotate in the stator chamber C.

The rear flange or rib 7 of the stator is formed with a hub portion 36, in which is 10 fixed a hollow metal plug or bearing 37, as shown in Fig. 5. The bushing 35 of the rotor extends into the bearing plug 37, which thus forms a rear support for the rotor. The front support of the rotor is 15 formed by a hollow shaft 38 which passes through the bracket K and rotor bushing 34. That portion of the hollow shaft 38 which passes through the bushing 34 is screw-threaded to engage the screw-threads 20 of the bushing 34, whereby the shaft 38 is rigidly secured to the rotor for operating the same. A nut 39 at the inner end of shaft 38 holds the latter rigidly connected to the rotor.

25 The supporting bracket K on which the stator S is mounted, as previously described in detail, is secured to a plate indicated as a whole by D. This plate, which is preferably shaped out of sheet metal, consists of 30 an annular rim 40 and a recessed or cup-shaped portion 41 extending rearwardly from the rim. The rim 40 has a number of holes 42 for receiving screws 43 or other fastening devices, by means of which the 35 disk is secured to a suitable panel P. This panel may be the front wall of a box or cabinet containing the different units of a radio receiving set. The panel has an opening 44 through which extends the cup-shaped portion 41 of the supporting plate D. The 40 bracket K is secured to the rear wall of the cup-shaped portion 41 by screws 45, or other fastening devices, passing into holes 46 in the plate 10 of bracket K. Thus it is seen 45 that the entire instrument is supported on plate D. By virtue of this arrangement, it is a very simple and easy matter to mount the instrument in proper position on a panel.

When I refer to the rim 40 as annular, I 50 do not mean that its outer edge or boundary must be circular, for it is obvious that the geometric outline of the rim 40 is immaterial, as long as it provides a flange around the cup-shaped portion 41 for securing the 55 plate D and all parts carried thereby to the supporting panel. Also, it will be clear that in the broader aspect of my invention it is immaterial whether the rim 40 engages the outer or inner side of the panel. When the 60 rim 40 is fastened against the outside of the panel, it may serve the additional function of carrying a scale or index, as later explained.

To the outer end of rotor shaft 38 is secured a finger piece which is shown in the

form of a bar 47. As shown in Figs. 3 and 5, the bar 47 has a central hole a for receiving the cylindrical extension b of a nut c which is screwed to the outer end of shaft 38. The head of nut c lies in a recess d surrounding hole hole a. It will be understood, of course, that any other suitable connecting means between shaft 38 and bar 47 may be employed. The shape of the finger bar 47 is such that it fits within the recess 70 41 of plate D, so as to be substantially flush with the rim 40. This does away with the objectionable protruding knobs of prior radio units, enhancing the neatness and compactness of the radio set in which the instrument is used. Although housed within a recess, the bar 47 is easily gripped by the fingers. I prefer a bar to a knob for several reasons. In the first place, the bar 47 is more easily and naturally gripped by the 80 fingers than a knob, so that a fine adjustment of the rotor can be easily made. Also, the bar itself acts as a pointer by simply providing a suitable mark or indicator 48 at one end thereof to cooperate with a scale 49 85 on the rim 40 of plate D. This is shown in Fig. 1. Another advantage of bar 47 is that it may be recessed to receive a smaller knob in instruments where a double adjustment is required, as in varicouplers, vernier 90 condensers, and the like. I will presently come to that particular feature of my invention.

In order to limit the rotary movement of bar 47 in either direction, I provide a stop 100 pin 50, which may be in the form of a set-screw fastened in the plate 10 of bracket K and projecting into the recess 41 of plate D, as shown in Fig. 5. On the rear face of bar 47 are formed two slots 51 arranged to receive the stop pin 50 when the bar 47 reaches the limit of its movement in either direction.

I will now describe the tap switch that is mounted on the rotor as a part of the instrument and is connected to different 110 points in the rotor winding. Within the rotor shell is mounted an insulated disk 52, which may be curved or dished to conform generally to the spherical contour of the rotor shell. The disk 52 has a non-circular 115 opening 53 adapted to fit over a correspondingly shaped extension 54 of the rotor shell member 24, as shown in Fig. 5. The nut 39 holds the disk 52 firmly in position. If desired, a metal plate 55 may be interposed 120 between the nut 39 and the disk 52. On the insulating disk 52 is mounted a series of metal contacts 56. In the present instance, I have shown eight of these contacts, but the number may vary. To each contact 56 is electrically connected one end of a conductor 57. The other ends of conductors 57 are connected to different points in the rotor winding 33, which is here assumed 125 to be the primary winding. In order to en- 130

able this tapping of the rotor winding by means of conductors 57, I provide the rotor shell member 24 with holes 58, as best shown in Fig. 9. Portions of the rotor winding 5 protrude through holes 58 and thus permit connections to be made with the conductors 57. Although there are eight switch contacts 56, with a corresponding number of conductors 57, it will be seen from Fig. 9 10 that there are nine openings 58. This extra opening is for the purpose of allowing a connection to be made between the two parts or sections of the rotor winding by means of a conductor 59, as indicated in 15 dotted lines in Fig. 6.

Referring to Fig. 5, it will be seen that a rod 60 extends through the hollow rotor shaft 38. On the outer end of rod 60 is fixed a knob 61, which is held in position 20 by a nut 62 or otherwise. The knob 61 is preferably housed in a recess 63 formed in the central portion of the finger bar 47. In this way, the knob 61 is mounted substantially flush with the finger piece 47 and 25 does not project beyond the rim 40 of the supporting plate D. On the screw-threaded inner end 64 of rod 60 is secured a switch arm 65 of good conducting material. In Fig. 5, the switch arm 65 is shown clamped 30 between a pair of nuts 66. When the knob 61 is turned, the switch arm 65 moves over the contacts 56 and taps the rotor coil at the particular point to which the engaged contact is connected. In order to enable 35 the operator to determine how many sections of the rotor winding are connected in circuit, I provide suitable marks on the front of the knob. In the particular construction shown in the drawings, the rotor winding is tapped at eight points and so I 40 place the numerals 1 to 8 on the knob 61. The bar 47 has marked thereon an indicator 67, which acts as a stationary index for the numerals on the knob 61. For instance, in 45 Fig. 1 the knob 61 is in such position that the indicating numeral 1 is opposite the mark 67. This means that the switch arm 65 is on the first contact 56, which would be 50 the extreme right contact as viewed in Fig. 6. When the indicating numeral 8 of the dial is opposite the mark or pointer 67, the switch arm 65 engages the last of the switch contacts, as shown in Fig. 6. To limit the 55 movements of switch arm 65 between the first and last of the contacts 56, I provide suitable stops 68, which may conveniently be made in the form of bent clips secured to the first and last contacts. It will be clear 60 that the contacts 56 and the arm 65 constitute a tap switch for the primary winding 33.

It should be understood that the rod 60 is freely rotatable in the hollow shaft 38 without moving the rotor itself. After the tap

switch has been adjusted by turning the 65 knob 61, as explained, the operator grasps the bar 47 and knob 61 as if they were a single member, and they turn as a unit to control the rotor. I need not explain that the object of turning the rotor one way or 70 the other is to adjust the inductive relation of windings 16 and 33, because this point is well understood by radio engineers. It will be clear, then, from what I have said, that when the rotor is adjusted, the tap switch 75 mounted thereon moves with it as a part thereof, so that a previous adjustment of the switch is not disturbed.

By mounting the tap switch on the rotor as a part of the instrument, I dispense with 80 the necessity of a separate tap switch outside of the instrument, as is required in the case of variocouplers and other tuning instruments heretofore constructed. My new arrangement of tap switch not only simplifies 85 the instrument and the receiving set as a whole, but adds to the neatness and compactness of the same. The nested arrangement of the finger bar 47 and switch knob 61 prevents these parts from protruding beyond 90 the panel on which the instrument is mounted.

A binding post 69 is screwed into the metal bearing plug 37, as best shown in Fig. 5, and bears against a coiled spring 70 95 mounted in the bushing 35 of the rotor. The binding post 69 is intended to receive one end of the antenna wire. The spring 70 is of conducting material and the outer end thereof is electrically connected to the leading-out wire 71 of the primary coil 33. The spring 70 is thus a yieldable conductor which insures a positive electric connection between one end of the primary coil and the binding 100 post 69. The other end of the primary winding 33 is grounded through switch arm 65, shaft 38, metal bracket K and metal plate D, which is connected to the ground, as diagrammatically indicated at G in Figs. 2 105 and 5.

As I said before, I prefer to make the supporting plate D of metal. This not only gives a plate of the required strength, but permits the plate to be grounded to the primary winding of the instrument. This 115 grounded plate acts as a shield against the capacity effect of the operator's hand or body, thereby eliminating a disturbing factor in tuning the circuit.

In Figs. 11 and 12, I have shown what 120 is commonly called a variometer. As many of the structural details of this instrument are substantially identical with corresponding parts in the variocoupler above described, I need not repeat a detailed description of these common features. In briefly describing Figs. 11 and 12, I will use the same reference characters as in the preced-

ing figures to indicate like or corresponding parts, except that I will use prime marks for the sake of distinction.

The stator S' is mounted on a bracket K', which is secured to the back of a supporting plate D', substantially in the manner previously described in connection with parts S, K and D. Within the chamber of the hollow stator S' operates a rotor R', which is controlled by a finger bar 47'. The insulating shells or frameworks of the stator S' and rotor R' are substantially the same as those of stator S and rotor R, previously referred to. On the inside wall of stator S' is mounted a winding 16', and on the outside of rotor R' is a winding 33'. As is usual in variometers, the two windings are connected together in series by conductors v and v', which pass through the bushing 35' of the rotor. One end of the connected winding goes to a binding post 19' and the other to a binding post 20'.

What I have previously said about the advantages of the various novel features in the variocoupler applies equally well to the variometer shown in Figs. 11 and 12, except that in the latter case no tap switch is required.

As I previously stated, in the broader aspect of my invention, the rotor coil may be the primary or the secondary. There are, however, certain advantages in making the rotor coil the primary. In variocouplers heretofore constructed, where the rotor coil is the secondary and where the primary is the stator coil to which a tap switch is connected, the adjusting of the coupling between the two windings by turning the secondary causes a disturbance in the adjustment of the inductive relation between the secondary of the variocoupler and such other tuning units as are connected in the circuit or circuits of the secondary winding of the variocoupler. Such a disturbance of previously adjusted inductive relation is highly objectionable and undesirable, and makes the tuning complicated and difficult.

Now, in my invention, by making the rotor coil the primary, I eliminate the foregoing objection and difficulty because the position of the secondary winding of the variocoupler is not altered with relation to the other units in the tuning circuit when the coupling between the variocoupler coils is adjusted by moving the primary. This construction has the further advantage that it allows greater latitude in mounting the various tuning units of the entire outfit in relation to each other.

Although I have explained my invention in connection with a variocoupler and a variometer, it is clear that certain features are applicable to all radio instruments requiring adjustment in tuning a radio receiving circuit, such as variable condensers, variable

rheostats, potentiometer, and so forth. All of these and other devices used for like purposes may be classed as radio tuning instruments, to which my invention is applicable in its broader aspects. I would also have it understood that, although I have herein shown and described certain specific structures, it is obvious that the various features of my invention may be mechanically embodied in other forms than herein set forth. 75

I claim as my invention:

1. In radio tuning apparatus, a recessed or cup-shaped supporting plate provided with a surrounding rim whereby said plate is adapted to be mounted on a panel so as to be practically flush therewith, a rotary hand member mounted in the recess of said plate, whereby said member is practically flush with the panel, an electrical device secured directly to said plate and supported thereby, and means for operatively connecting said hand member with said device to control the same. 80

2. In radio tuning apparatus, a recessed or cup-shaped supporting plate adapted to be mounted on a panel so as to be practically flush therewith, a pivoted bar mounted in the recess of said plate, whereby said bar is practically flush with the panel, an electrical device secured directly to said plate and supported thereby, and means for operatively connecting said bar with said device to control the same. 85

3. In radio tuning apparatus, a supporting plate comprising a recessed or cup-shaped portion surrounded by a rim having a scale, a pivoted bar mounted in said recessed portion of the plate so as to be practically flush with said rim, an indicator on said bar to cooperate with said scale, an electrical device secured directly to said plate and supported thereby, and means for operatively connecting said bar with said device to control the same. 100

4. In radio tuning apparatus, a plate comprising a recessed or cup-shaped portion surrounded by a rim and adapted to be secured to a panel, a centrally pivoted bar mounted in said recessed portion of the plate so as to be practically flush with said rim, said bar having a central recess, a rotary knob nested in the recess of said bar, and electrical devices independently controlled by said bar and said knob. 115

5. In radio tuning apparatus, a supporting plate comprising a recessed or cup-shaped portion surrounded by a rim and adapted to be secured to a panel, a plurality of nested hand members coaxially pivoted in said recessed portion so as to be practically flush with said rim, electrical devices secured directly to said plate and supported thereby, and connections between said hand members and said devices for independently controlling said devices. 120

6. In radio tuning apparatus, a plate comprising a recessed or cup-shaped portion surrounded by a rim having a scale, a centrally recessed bar pivoted in said recessed portion of the plate so as to be practically flush with said rim, an indicator on said bar to cooperate with said scale, a rotary knob nested in the recess of said bar and having a dial, a second indicator on said bar adapted to cooperate with said dial on the knob, and electrical devices independently controlled by said bar and said knob.
- 10 7. As a new article of manufacture for supporting a radio tuning unit, a supporting plate adapted to be secured to a panel and comprising a recessed or cup-shaped portion surrounded by a rim, said recessed portion having a flat bottom or rear section of substantial area for attaching thereto a tuning unit.
- 15 8. As a new article of manufacture for supporting a radio tuning unit, a one-piece sheet-metal plate adapted to be secured to a panel and comprising a recessed or cup-shaped portion surrounded by a rim, said recessed portion having a flat bottom or rear section of substantial area for attaching thereto a tuning unit.
- 20 9. In radio tuning apparatus, a plate adapted to be secured to a panel and having a recessed portion extending rearwardly, a variable tuning unit mounted on the recessed portion of said plate, and a hand member pivoted in said recessed portion for controlling said unit.
- 25 10. In radio tuning apparatus, a plate adapted to be secured to a panel and having a recessed portion extending rearwardly, a bracket secured to the rear wall of said recessed portion, a variable tuning unit mounted on said bracket, and a hand member pivoted in said recessed portion for controlling said unit.
- 30 11. In radio tuning apparatus, a plate adapted to be secured to a panel and having a recessed portion extending rearwardly, a variable tuning unit mounted on the recessed portion of said plate, and a pair of nested hand members pivoted in said recessed portion for controlling said unit.
- 35 12. In radio tuning apparatus, a plate adapted to be secured to a panel and having a recessed portion extending rearwardly, a bracket secured to the recessed portion of said plate, a variable tuning unit mounted on said bracket, and a pair of nested hand members pivoted in said recessed portion for controlling said unit.
- 40 13. In radio tuning apparatus, a plate adapted to be secured to a panel, a bracket mounted on the back wall of said plate and provided with a pair of rearwardly projecting flanges, and a tuning unit secured to said flanges.
- 45 14. In radio tuning apparatus, a plate adapted to be secured to a panel, a tuning unit mounted on the back wall of said plate, and a hand member extending through said plate for adjusting said unit.
- 50 15. In radio tuning apparatus, a plate adapted to be secured to a panel, a bracket mounted on the back wall of said plate, and a tuning unit secured to said bracket.
- 55 16. In radio tuning apparatus, a plate adapted to be secured to a panel, a bracket mounted on the back wall of said plate and provided with a pair of rearwardly projecting flanges, a stator having flanges arranged to fit against the flanges of said bracket, fastening devices passing through both sets of flanges, a rotor within said stator, and means for adjusting said rotor.
- 60 17. In radio tuning apparatus, a plate adapted to be secured to a panel, a bracket mounted on said plate and provided with a bearing, a fixed tuning element secured to said bracket, a rotary tuning element associated with said fixed element and supported at one end in said bearing, and means for supporting the other end of said rotary element on said fixed element.
- 65 18. In radio tuning apparatus, a panel, a grounded plate mounted on the front of said panel, and a tuning unit mounted on the back wall of said plate.
- 70 19. In radio tuning apparatus, a supporting panel provided with an opening, a metal plate mounted on the front wall of said panel and having a portion extending into said opening, a bracket secured to the back wall of said plate, and a variable tuning unit mounted on said bracket said metal plate being grounded to act as a capacity shield.
- 75 20. In radio tuning apparatus, a supporting panel, a grounded metal plate mounted on the front of said panel, and a tuning unit back of said plate and having a winding electrically connected at one end to said grounded plate.
- 80 21. In radio tuning apparatus, a panel, a metal plate on the front wall of said panel, a variable radio unit back of said panel, and a rotary hand member mounted in front of said plate for controlling said unit, said plate being grounded to act as a capacity shield.
- 85 22. In radio tuning apparatus, a variable tuning unit, an adjustable hand member for controlling said unit, a grounded metal shield between said unit and said hand member, and means for attaching said unit to said shield, whereby said shield forms a support for said unit.
- 90 23. In a radio tuning unit, an insulating shell having substantially the shape of a hollow spherical segment, said shell consisting of two complementary halves separated in a plane substantially parallel to the axis of the segment.
- 95 100 105 110 115 120 125 130

24. In a radio tuning unit, an insulating shell having substantially the shape of a hollow sphere with diametrically opposite sections cut away, said shell consisting of two complementary halves separated in a plane which passes through the planes of said cutaway sections.

25. In a radio tuning unit, a substantially spherical insulating shell consisting of two complementary halves, and a coil mounted on the outer surface of said shell, said shell halves being separated in a plane which cuts through the turns of the coil, whereby said coil binds the shell halves together.

26. In a radio tuning unit, a substantially spherical shell of insulating material having axially aligned metal bushings embedded therein, said shell consisting of two complementary halves separated along diametrical- 15 ly opposite lines lying in a plane substantially at right angles to the axis of said bushings.

27. In radio tuning apparatus, a supporting panel having an opening, a recessed or cup-shaped plate mounted on the front of said panel and projecting rearwardly into said opening, a stator supported on said plate and carrying the secondary winding, a rotor movable within said stator and carrying the primary winding, a tap switch mounted on said rotor and connected to the primary winding, a pair of rotary hand members concentrically mounted at the front of said plate so as to be substantially flush therewith, a connection between one of said members and the rotor, a connection between the other member and said switch, said connections being such that said switch is adjustable independently of the rotor and that said rotor and said switch are rotatable as a unit.

28. In radio tuning apparatus, a supporting panel having an opening, a recessed or cup-shaped plate mounted on the front of said panel and projecting rearwardly into said opening, a stator secured to the back wall of said plate and carrying the secondary winding, a rotor movable within said stator and carrying the primary winding, a tap switch mounted on said rotor and connected to the primary winding, a hollow shaft for operating said rotor, a recessed bar mounted substantially flush in said cup-shaped plate and connected to the outer end of said shaft, a rod extending through said shaft, an arm at the inner end of said rod and arranged to engage said switch contacts, a knob nested in the recess of said bar and connected to said rod, said knob being rotatable independently of said bar, a scale on said knob, and an indicator on said bar for said scale, said bar and knob being rotatable as a single member.

29. In radio-tuning apparatus, a supporting plate adapted to be secured to a sub- 15 stantially upright panel, a tuning unit mounted in a substantially horizontal position on the back wall of said plate, and a hand member extending through said plate and panel for adjusting said unit from the front of the panel.

30. In a radio tuning apparatus, the combination with a panel having an opening, of a plate having a rim adapted to be secured to the outer side of said panel and also having a recessed or cup-shaped portion projecting rearwardly through said opening, and a tuning unit secured to said recessed portion so as to extend rearwardly of said panel.

31. In radio tuning apparatus, the combination with a panel having an opening, of a plate having a rim adapted to be secured to the outer side of said panel and also having a recessed or cup-shaped portion projecting rearwardly through said opening, 20 said rim being provided with a scale, a variable tuning unit secured to said recessed portion so as to extend rearwardly of said panel, an adjustable hand member in said recessed portion for controlling said unit, and indicating means associated with said hand member to cooperate with said scale.

32. In a radio-receiving set, the combination with a supporting panel having an opening, of a plate having a flange or rim adapted to fit against the outer wall of said panel for mounting said plate on the panel, an extension on said plate projecting through said opening, and a tuning unit secured to said extension.

33. In a radio-receiving set, the combination with a supporting panel, of a plate having a flange or rim adapted to fit against the wall of said panel for mounting said plate on the panel, a variable tuning unit, means for attaching said unit to said plate in such position that the unit extends inwardly from said panel substantially at right angles thereto, and a hand member at the front of said plate for controlling said unit.

34. In an electrical tuning unit, a stator consisting of two similar shell sections fitted together, the adjacent edges of said sections being provided with pairs of ears, a supporting member for said shell sections, said member comprising a plate provided with projections extending at right angles to the plane of said plate, said projections being arranged to fit between the ears of said shell sections, and fastening devices passing through said ears and said projections for securing the shell sections together and to said plate, said plate being adapted to be securely fastened to a suitable support.

35. In radio tuning apparatus, the combination with a panel, of a tuning unit having a fixed part and a movable part, a separate bracket fastened to the fixed part of said

unit and having a laterally projecting supporting surface for receiving fastening means to secure the bracket to said panel, whereby said unit is supported in proper position on the panel, and a member at the front wall of said panel for manually adjusting said movable part.

36. In radio tuning apparatus, a variable tuning unit having a rotatable shaft for varying the electrical effect of said unit, and a separate bracket on said unit for securing the same to a panel in such position that said shaft extends practically at right angles to the plane of the panel, said bracket having a laterally projecting supporting surface to receive fastening means and thereby firmly secure the bracket and unit to the panel.

37. In an electrical tuning unit, the combination of a rotary knob and a rotary bar concentrically mounted for independent rotation, said bar being recessed to receive said knob, an electrical member operated by said knob, and an electrical member operated by said bar.

38. In an electrical tuning unit, the combination of a rotary knob and a rotary bar concentrically mounted for independent rotation, said bar being recessed to receive said knob, means whereby said knob and said bar are rotatable as a unit, means whereby said knob is rotatable independently of said bar, an electrical member operated by said knob, and an electrical member operated by said bar.

39. In an electrical tuning unit, the combination of a rotary knob and a rotary bar

concentrically mounted for independent rotation, said bar being recessed to receive said knob, means whereby said knob is rotatable independently of said bar, an electrical member operated by said knob, an electrical member supported by said bar, an outer dial for said bar, and a dial on said knob arranged to cooperate with an indicating mark on said bar.

40. In radio tuning apparatus, a supporting bracket comprising a base whereby the bracket may be mounted on a panel, a hub extending from said base, an arm projecting from said base, an electrical member secured to said arm, a rotary shaft extending through said hub, and a second electrical member rotatable by said shaft.

41. As a new article of manufacture for use in radio tuning apparatus, a supporting bracket consisting of a single casting comprising a base whereby the bracket may be secured to a panel, a hub extending from said base substantially at right angles to said base, and an arm projecting from said base, for the purposes specified.

42. A device of the character described, comprising a bracket including a tubular member terminating at its one end in a laterally extending base flange, an arm extending from the base flange disposed at an angle to the tubular member, a shaft turnable within the tubular member, a coil supported by the arm, and a second coil supported by the shaft and within the first named coil.

STANLEY D. LIVINGSTON.
